O. FRISK

STEPLADDER

Filed March 18, 1927

Patented Nov. 8, 1927.

UNITED STATES PATENT OFFICE.

OSKAR FRISK, OF NEW YORK, N. Y.

STEPLADDER.

Application filed March 18, 1927. Serial No. 176,460.

This invention relates to improvements in step ladders.

The primary object of the invention resides in a step ladder of the self supporting type and which may be adjusted for reaching a relatively great height, or in instances where a tall ladder could not be erected, the same may be folded to a shorter height to meet the occasion.

10 Another object of the invention is to provide a step ladder having supporting legs with added extensions hinged thereto, the lower step of the ladder serving as a means for locking the extensions of the front legs in an extended position when the full length of the ladder is desired and which extensions may be folded back upon the respective legs to reduce the height of the ladder when used in a restricted place.

20 A further object of the invention is the provision of a step ladder of the kind above mentioned which is simple in construction, easy to adjust, and strong and durable for the purpose intended.

25 With these and other objects in view, the invention resides in certain novel construction and combination and arrangement of parts, the essential features of which are hereinafter fully described, are particularly 30 pointed out in the appended claims, and are illustrated in the accompanying drawing, in which:—

Figure 1 is a perspective view of my improved step ladder in an extended position.

35 Figure 2 is a side elevational view of the ladder in a folded position.

Figure 3 is a detail sectional view through the removable step.

40 Figure 4 is a perspective view of the removable step.

Referring more particularly to the drawing, the reference numeral 10 designates my improved step ladder in its entirety and which includes spaced parallel front legs 11, 45 11 having steps 12 secured thereto. The top of the legs support a platform 13 and swingingly mounted to the platform is a prop 14 which includes spaced legs 15. Foldable brace bars 16 are connected to the prop and 50 the front legs to limit the separation of the same. Hingedly connected to the front legs 11, 11 as at 17 are leg extensions or sections 18. The hinges 17 are fastened to the outer side faces of the legs and leg sections with 55 the knuckles or barrel of the hinges disposed above the bottom of the legs so that the said

legs may rest flat against the supporting surface. The lower leg sections are braced by a removable step 19 which co-acts to lock the sections against outward swinging movement 60 when in a set-up position. The ends of the step 19 are provided with ears 20 which extend through aligned slots 21 provided in the lower leg sections. The ears are provided with slots 22 for receiving wedge keys 23 65 which engage the outer side faces of the leg sections 18 for locking the step against accidental separation.

The legs 15, 15 of the prop are of the same length as the front legs 11 and have leg sections or extensions 24 hinged thereto as at 25. The knuckles or barrels of the hinges are disposed above the lower ends of the legs 15 to permit the legs to rest flat against a supporting surface when the leg sections 75 are in a folded position. For locking the joint between the legs 15 and the leg sections 24, I provide keepers 26 on the legs 15 and the corresponding leg sections 24 and which keepers receive wedges 27 which bridge the 80 joint therebetween and further serve to strengthen the joint. The hinges 25 unlike the hinges 17 are mounted on the inside edges of the legs 15 and the leg sections 24 so that the leg sections may swing inwardly when 85 in a folded position to lie flat against the leg sections 15.

When the leg extensions are extended into the position shown in Figure 1 of the drawings and are locked by the wedges, the same 90 provides a ladder of a relatively tall height for use when it is desired to reach corresponding heights. However, should it be desired to set-up the ladder in a room having a relatively low ceiling, the leg sections 18 and 95 24 are folded back upon the legs 11 and 15 as shown in Figure 2 of the drawing and are held in such position by hooks 28 carried by the legs proper and which engage eyes 29 provided on the extensions. It will, of course, be understood that the wedges and step are first removed before swinging the sections to a folded position.

A ladder of this kind is especially adapted for household purposes and it will be found useful by painters, paper hangers and carpenters for working in rooms where the average height ladder could not be erected.

What is claimed as new is:—

1. A step ladder comprising a pair of 110 spaced legs having steps supported thereon, auxiliary leg sections hinged to the lower

ends of said legs, a step removably supported by said leg sections, ears provided on the ends of said step for passage through aligned slots provided in said leg sections, said ears having slots therein, and wedges passing through said last mentioned slots and engaging the sides of said leg sections, substantially as and for the purpose specified.

2. A step ladder comprising front and rear legs movable to a position in diverging relation to each other, extension legs hinged

to the lower ends of the respective legs and foldable thereagainst, the joint of each hinge being disposed inwardly from the lower end of the leg to allow the leg to rest flat upon a supporting surface when said extension is folded, and locking means for holding said extension legs in co-extensive position with the respective front and rear legs.

In testimony whereof I have affixed my signature.

OSKAR FRISK.
